UNITED STATES PATENT OFFICE.

JOHN F. HENDRIKSON, OF BOSTON, MASSACHUSETTS.

RAILWAY-SWITCH.

SPECIFICATION forming part of Letters Patent No. 507,616, dated October 31, 1893.

Application filed March 15, 1893. Serial No. 466,014. (No model.)

To all whom it may concern:

Be it known that I, JOHN F. HENDRIKSON, of Boston, county of Suffolk, State of Massachusetts, have invented an Improvement in 5 Railway-Switches, of which the following description, in connection with the accompanying drawings, is a specification, like letters on the drawings representing like parts.

My invention relates to a switch especially 10 intended for use in street railways the object being to provide a switch and actuating mechanism therefor that can be operated from the platform of the approaching car.

The switch proper may be the usual pivoted tongue such as commonly employed in 15 street railways, and at each side of the track approaching the point of the switch are arranged pivoted levers or treadles the upper surface of which is preferably just outside of 20 and slightly below the top of the rail. The said treadles or switch levers oscillate in a vertical plane and engage by a cam or incline with another lever pivoted on a vertical axis to turn in a horizontal plane, or toward and 25 from the side of the rail.

The lever on the side of the track at which the switch point operates is provided with a projection working through an opening in the web of the rail so as to engage the pivoted switch tongue near its point and the corresponding lever at the other side of the track engages with one end of a rod or push bar extending across between the rails of the track and into engagement with the switch 30 tongue at the opposite side thereof from the lever first mentioned. Thus the downward movement of either one of the treadle levers produces a corresponding inward movement of the end of the corresponding horizontal 35 lever which engages directly or indirectly through the rod with the switch tongue and throws the point of the tongue away from the side at which the treadle was depressed.

The cross rod or connection is preferably 40 made yielding to avoid breakage of the parts if there should be any obstruction.

The car is provided at both ends, or at the forward end only if it is intended to always run in one direction, with two treadle 45 pressers arranged in advance of the wheels of the car and normally held above the road surface but adapted to be depressed by a suitable handle or foot piece on the car plat-

form so that as the car advances they will bear upon the surface of the treadle lever to 55 depress the same and thus operate the switch.

Figure 1 is a plan view partly in section and with portions of the inclosing covers removed of a switch apparatus embodying this invention; Fig. 2 a side elevation thereof 60 showing also the car with one of the treadle depressers in position to operate the corresponding treadle; Fig. 3 a vertical section on broken line x^3 , Fig. 1, on a larger scale, and Figs. 4 and 5 sectional details of a modified 65 construction.

The apparatus is applicable to a track A of any usual construction, and comprises a switch point proper a which may be the usual tongue or point pivoted at a^2 where the lines 70 of the track diverge. At each side of the track A leading to the switch point a a treadle or lever b is pivotally connected at b^2 with the web of the rail or any other convenient support, said lever being mainly inclosed in a 75 cover B but having a tread portion b^3 which is exposed through an opening in said cover and lies at the outside of the adjacent rail A preferably standing normally in a slightly inclined position with the highest part at or 80 slightly below the level of the top of the rail as shown in dotted lines Fig. 2. The free end of the treadle lever may thus swing in a vertical plane at the side of the rail and it is restrained from lateral movement away from 85 the rail by a bracket or guide c which may be bolted to the rail or otherwise fastened in proper position with relation thereto, the rail together with the said bracket resisting lateral thrust in either direction on the free 90 end of the lever b . The extremity b^4 of each of the treadle levers b , is inclined to the vertical as best shown at the right hand side in Fig. 3, and enters a correspondingly inclined slot in the end of a switch actuating lever d 95 turning on a vertical pivot or fulcrum at d^2 .

The lever d on the same side of the track as the switch tongue a is provided with a lateral projection d^3 extending through an opening in the web of the rail A or of the switch casting so as to bear against the side of the switch tongue a as clearly shown in Figs. 1 and 3. The end d^3 , of the lever at the other side of the track is connected with or bears against a rod or push-bar e extending through a hole 100 in the web of the rail and across the tracks 105

through a suitable box or casing E and terminating near the other side of the switch tongue *a* from that engaged by the projection *d*³.

5 Owing to the inclination of the extremity *b*⁴ of the treadle lever and the corresponding notch in the lever *d*, the former has a cam or wedge-like action on the latter so that when one of the treadle levers *b* is depressed it 10 causes the slotted end of the corresponding lever *d* to be thrown outward, and the free end of the said lever *d* to be thrown inward toward the side of the switch tongue *a* and by engagement therewith to turn the latter 15 on its pivot, throwing the point of the switch away from the side of the track at which the treadle was depressed.

The treadle levers *b* are normally retained in elevated position, by springs *b*⁵ acting 20 thereon as best shown in Fig. 2, and thus normally retain the horizontal levers *d* retracted, with the projection *d*³ and the rod *e* out of engagement with the sides of the switch tongue which is thus free to turn in either direction 25 in the usual way or by whichever one of said levers is operated, if the switch tongue is not already in proper position upon the approach of the car. The switch may thus be thrown if required by an operator on the approaching 30 car causing one or the other of the treadle levers to be depressed, and in order to facilitate this operation the car is provided with treadle depressers, one at each side, consisting essentially of a wheel or roller *g* supported 35 at the end of an arm *h* on a rock shaft *i* provided with a pulley *i*² to which is connected a cord or chain *k* extending to a pulley *m* under the front of the platform provided with an operating rod *m*² extending up through the 40 platform and having a suitable foot piece *m*³ above the platform to be engaged and depressed by the foot of the attendant in charge of the car.

A spring *i*³ tends to raise the treadle depresser and normally holds it at some distance 45 above the road bed but when the attendant depresses the corresponding knob *m*³ the depresser is lowered so that the wheel *g* runs along the road bed in proper position to engage with the inclined portion *b*³ of the treadle and depress the latter. The wheel *g* has a portion *g*² of smaller diameter properly located to engage with the track rail *A* while the portion of the wheel of larger diameter 55 outside the track rail extends below the level thereof and thus operates properly to depress the treadle lever *b*. The wheel or treadle depresser *g* is thus held down to its work by the pressure applied to the knob *m*³ by the attendant, and if the wheel of the depresser should meet any obstruction on the track, or if there should be any positive obstruction to the movement of the switch or parts that act directly thereon, the wheel of the depresser 60 would be caused to yield and no breakage of the working parts would take place.

The rod *e* is preferably made in two parts telescopically connected together as shown at 70 *e*³ Figs. 1 and 3, and acted upon by a spring *e*⁴ which tends to separate the two parts and retain the rod at its normal length, the said spring being stiff enough to overcome any normal resistance to the movement of the switch tongue but yielding in case there is any obstruction that might otherwise cause 75 a breakage to the parts.

The yielding or telescopic joint may be at the point where the rod *e* connects with the end *d*³⁰ of the lever as shown in Fig. 5, instead of in the rod itself, and the projection *d*³ of the lever on the side of the track adjacent to the switch tongue may also have a yielding, sliding, or telescopic connection with the corresponding lever as shown in Fig. 4.

In the construction shown in Figs. 4 and 5, 80 the spring *e*³⁰, contained in a suitable recess or spring chamber in the lever performs the same function and operates in the same way as the spring *e*³ shown in Figs. 1 and 3.

The herein described mechanism is simple 90 and at the same time very strong and durable and is well protected from the entrance of material from the road surface that would be likely to interfere with the proper operation. 95

I claim—

1. The combination of the movable switch with vertically movable treadles pivoted one at one side and the other at the other side of the track and adapted to be operated from the car approaching the switch, horizontally movable levers actuated by the said treadle levers, and acting one against one and the other against the other side of said movable switch, substantially as described. 105

2. The combination of the movable switch with vertically movable treadle levers one at each side of the track, horizontal levers operatively connected therewith, one of which is adapted to engage directly with one side of the switch, and a rod or push bar extending from the other lever across the track to the other side of said switch, substantially as described. 110

3. The combination of the movable switch 115 with vertically movable treadle levers one at each side of the track, horizontal levers operatively connected therewith, one of which is provided with a projection to engage with one side of the switch, and the rod or push-bar extending from the other lever across the track to the other side of said switch and a yielding connection between the lever and the switch engaging portion, substantially as described. 120 125

In testimony whereof I have signed my name to this specification in the presence of two subscribing witnesses.

JOHN F. HENDRIKSON.
